UNITED STATES PATENT OFFICE.

ARTHUR F. O'CONNOR, OF CHICAGO, ILLINOIS, ASSIGNOR TO UNION RAILWAY EQUIPMENT CO., OF CHICAGO, ILLINOIS, A CORPORATION OF ILLINOIS.

SEPARABLE COUPLER-RELEASE RIGGING.

Application filed May 1, 1924. Serial No. 710,289.

My invention relates to coupler release rigging and more particularly to a separable connection between the eye on the coupler release lever and the eye on the coupler lock. It is a purpose of my invention to provide means for connecting the lock on the coupler with the release lever in such a way that it is unnecessary to take down the coupler when replacing the connection between the lever and said lock. By providing means for separating the connecting member so that the same will be divided between the eye on the release lever and the eye on the locking pin the replacement of this connection is made possible without taking down the coupler. Also, in case it is desired to replace the uncoupling lever the same can be much more readily removed where a separable connection is provided in the means connecting the release lever and the locking pin than where a permanent connection between the parts is provided.

In the present methods of connecting levers and coupler locks much inconvenience results due to the fact that it is necessary to remove either the coupler lock or the lever in order to make the necessary connection between the parts. With the device embodied in the present invention the coupler release rigging can be separated and each part hooked onto the lever or coupler lock and then connected up making a substantial connection which is easily and quickly applied without making it necessary to disturb either the coupler lock or the uncoupling lever. Further, with any of the previously used devices it is necessary to open up the eyes in the ends of the release rigging connection between the lever and the lock in order to separate the lever and lock and in doing this quite often the eye is so damaged that the release rigging can not again be used. By providing a readily separable connection in the rigging between the end thereof connecting with the uncoupling lever and the end thereof connecting with the lock, this difficulty is avoided.

The rigging preferably comprises an upper member of malleable iron formed with an eye thereon which is left open before application to the uncoupling lever so as to make it easy to apply and which eye is, of course, closed upon application of the device to the uncoupling lever. Said portion

of the device preferably comprises a housing having means therein for engaging with the lower portion of the connection or lock engaging member, said means normally holding the coupler lock engaging member in assembled relation with the member engaging the lever. The said lower member is, of course, also provided with an eye that engages with the eye in the coupler lock and this eye is also preferably left open for convenience in applying the device to the locking pin.

While numerous means may be provided for detachably connecting the two members comprising the connection between the uncoupling lever and the lock together, preferably this means comprises a pair of latches or triggers that are mounted in the housing which are adapted to engage a suitable formation on the lower member of the connecting means to prevent dis-engagement of said lower member from the upper member, but which latches or triggers are adapted to be moved to such a position as to permit the lower member to pass outwardly through the bottom of the upper member to disengage said members from each other, whereupon the uncoupling lever and the coupler are separated from each other so that either can be operated on without affecting the other.

Other objects and advantages of the invention will appear as the description of the accompanying drawings proceeds. However, I desire to have it distinctly understood that I do not intend to limit myself to the exact details shown or described but that I intend to include as part of my invention all such obvious changes and modifications of parts as would occur to a person skilled in this art and as would fall within the scope of the claims.

In the drawings:

Fig. 1 is a fragmentary end view of a portion of a railway car, showing the uncoupling lever and a portion of the coupler, the coupler being partly broken away;

Fig. 2 is a fragmentary side elevational view of the end portion of a railway car and a portion of the car coupler, showing the unlocking lever and the connection between the locking pin and said unlocking lever embodying my invention;

Fig. 3 is a view, partly in elevation and

partly in longitudinal section, of my improved connecting member, between the unlocking lever and the lock;

Fig. 4 is a similar view taken substantially at right angles to Fig. 3;

Fig. 5 is a section taken on the line 5—5 of Fig. 3;

Fig. 6 is a section taken on the line 6—6 of Fig. 4; and

Fig. 7 is a fragmentary section of a slightly modified form of device taken substantially on a plane corresponding to that of Fig. 5.

Referring in detail to the drawings, in Fig. 1 is shown a railway car 10 which is provided with a coupler 11 and on which is mounted the usual coupler release lever 12 having the handle portion 13 and having an arm 14 extending outwardly therefrom which is provided with an eye 15 at the end thereof. The coupler 11 is provided with the usual locking pin 16 having an eye 17 therein which is connected with the eye 15 by some suitable expandible and contractible connection. The most common means is a chain but many disadvantages of this connection exist which have caused numerous other forms of connections to be developed and the connecting means embodying my invention is intended to take the place of such flexible members as the chains referred to.

The particular connecting means that I provide between the eye 15 and the eye 17 comprises a member 18 having an eye 19 which is normally left open before application to the coupler, as will be clear from Fig. 4, said eye 19 engaging with the eye 15 to thus connect the member 18 with the unlocking lever 12. The member 18 is further provided with a suitable housing 20 having a chamber 21 therein and which is provided with a pair of ribs 22 on opposite faces thereof, the purpose of which will be described below.

It will be noted that the chamber 21 widens out toward the bottom of the member 18 and that a pair of openings 23 is provided in the sides of the housing 20, said openings further having lateral recesses or slots 24 therein in which the integral pivot members 25 of the latch members 26 are mounted. Said members 26 are provided with actuating fingers 27 extending rearwardly therefrom out through the openings 23 and are further provided with upper substantially flat faces 28, curved front faces 29 and a curved nose portion 30 that connects the curved front end portion 29 with a shoulder 31 provided on each of said members 26 which extend substantially at right angles to the face 32 of said member. The housing is provided with ledges 33 with which the lower faces 32 of the members 26 engage, the shoulders 31 thereon normally

engaging with the straight wall portions 34 of the bottom opening 35 in the housing 20. Said housing 20 is further provided with pairs of lugs 36 cast thereon that are in the dotted line position shown in Fig. 3 and which are adapted to be bent into the position shown in full lines in Fig. 3 by hammering on the same, thus causing said fingers 36 to engage with the pivot members 25 to hold the latch members 26 in position in the housing within the slots 24. As the members 25 rest in the slots 24 they are limited in their inward movement due to this fact and are limited in their outward movement due to the provision of the fingers 36. Recesses 37 are also provided in the housing 20 into which the latch members 26 are adapted to swing when the other member of the separable connection between the coupler lock and unlocking lever is inserted therein or when the fingers 27 are actuated to move the members 26 into such a position that the other half of the separable connecting means can be removed from the housing 20.

The coupler lock engaging member 38 is provided with an eye 39 which is normally left open, as shown in dotted lines in Fig. 4, prior to application to the locking member 16, which eye engages with the eye 17 and is closed after such engagement has been made. The member 38 is further provided with an upwardly extending shank portion 40 that has a head 41 thereon, said shank portion 40 being adapted to be received within the housing 20 and being preferably square in cross section, as shown in Fig. 6. The head 41, it will be noted, is substantially a T-head providing the shoulders 42 on opposite sides of the shank portion 40 and has rounded corners 43 on the upper side thereof, as will be clear from Fig. 3.

It will thus be seen that when the member 38 is inserted into the member 18 the rounded shoulders 43 will engage with the ends 30 of the members 26 moving the same upwardly or swinging the same on the pivot 25 so that one of said members moves clockwise and the other counter-clockwise around its axis, thus swinging said members gradually upwardly into the recesses 37 due to the fact that the rounded portions 43 engage with the rounded hook-like portions of the latches 26. After the head 41 has passed upwardly beyond said members 26 the members 26 will drop to the position shown in Fig. 3, locking the member 38 within the member 18. This action of the latches is facilitated due to the rounded ends 29 provided thereon. The members 38 and 18 will have a limited relative longitudinal axial movement due to the fact that the head 41 can move from the end wall 44 provided in the top of the housing 20 to the upper flat faces 28 on the latches 26. As the upper faces 28 are flat

on said latches and as the lower faces 32 are flat and the shoulders 31 are flat and engage with the walls 34, the latches will act substantially as a solid abutment for the head 41 at the lowermost limit of its movement. Thus, an extensible and contractible connection is provided between the eye 15 and the eye 17. Furthermore, relative rotation of the parts is prevented due to the provision of the ribs 22 which are substantially flat on the ends thereof and which engage with the flat faces of the squared shank portion 40 to thus prevent relative twisting of the eyes 19 and 39. This is very important as a twist of these eyes will sometimes prevent such flexibility in a connection as is necessary to obtain the desired operation of the unlocking pin by means of the locking lever, and also will prevent the dropping of the lock into locking position when coupling takes place.

If it is desired to separate the members 18 and 38 all that is necessary is to push downwardly on the fingers or triggers 27, thus swinging the members 26 upwardly so that the rounded noses 30 thereon will be spaced a greater distance apart than the width of the head 41, thus allowing the head 41 to pass downwardly beyond the latches 26 and the opening 35. This movement is, of course, usually merely relatively downwardly as in actual practice it would be the easiest to swing the unlocking member so as to swing the arm 14 upwardly, thus moving the housing 20 upwardly and pulling the same away from the member 18 when the head 41 will pass outwardly through the opening 35.

Instead of providing lugs such as shown in Fig. 5 for holding the fingers in position in the casing and to provide a pivotal mounting therefor, a slightly different arrangement can be used which is shown in Fig. 7. The casing 20' corresponding to the casing 20 of Fig. 5 is provided with an opening 23' through which the latch 26' projects, said latch being of substantially the same shape as the latch 26 shown in Figs. 3 to 5 inclusive. However, instead of providing lugs or pivot members on the latches, the latches are provided with a thickened portion 50 having an opening therein through which a pin 51 passes, said pin 51 extending through aligned openings in the lugs 52 on the casing 20'. A finger 27' for operating the latch corresponds to the finger 27 shown in Fig. 5. In order to remove the latches 26', the pins 51 would have to be removed and said latches normally rotate around said pins as an axis.

Having thus described my invention, what I desire to claim and secure by United States Letters Patent is:

1. The combination with an uncoupling lever and a coupler lock of extensible and contractible means connecting said lever and

lock comprising a pair of separable members, means for holding said members in assembled relation, and means for moving said holding means out of holding position.

2. The combination with an uncoupling lever and a coupler lock of extensible and contractible means connecting said lever and lock comprising a pair of separable members, means for holding said members in assembled relation, and means for moving said holding means out of holding position, said members having co-operating means thereon to prevent relative twisting of said members.

3. A device of the character described, comprising a pair of members movable axially relative to each other, one of said members engaging in the other of said members, means for holding said members detachably in engagement, and means for moving said members holding means out of holding position.

4. A device of the character described, comprising a member having a chamber therein, a member having a head thereon entering said chamber, said members having a limited relative longitudinal movement, and latches mounted in said first member for detachably holding said headed member in engagement therewith.

5. A device of the character described, comprising a member having a chamber therein, a member having a head thereon entering said chamber, said members having a limited relative longitudinal movement, and pivoted latches mounted in said first member for detachably holding said headed member in engagement therewith.

6. A device of the character described, comprising a member having a chamber therein, a member having a head thereon entering said chamber, said members having a limited relative longitudinal movement, and latches mounted in said first member for detachably holding said headed member in engagement therewith, said latches serving as abutments to limit the relative movement of said members in one direction.

7. A device of the character described, comprising a member having a chamber therein, a member having a head thereon entering said chamber, said members having a limited relative longitudinal movement, and latches mounted in said first member forming rigid abutments for detachably holding said headed member in engagement therewith, said chamber having means therein in engaging said headed member to prevent relative twisting of said members.

8. A device of the character described, comprising an open ended housing having attachment means on the closed end thereof, a headed member reciprocable in said housing and extending through the open end thereof, said member having attachment means on the opposite end thereof, and latch-

ing means forming rigid abutments for normally holding said headed member from passing entirely out of said housing.

9. A device of the character described, comprising an open ended housing having attachment means on the closed end thereof, a headed member reciprocable in said housing and extending through the open end thereof, and a pair of latches pivotally mounted in said housing for normally holding said headed member from passing entirely out of said housing.

10. A device of the character described, comprising an open ended housing having attachment means on the closed end thereof, a headed member reciprocable in said housing and extending through the open end thereof, and a pair of latches pivotally mounted in said housing for normally holding said headed member from passing entirely out of said housing, said housing having in-

ternal ribs thereon and said headed member having a squared shank portion to prevent relative turning of said members.

11. A device of the character described, comprising an open ended housing having an eye on the closed end thereof, a headed member reciprocable in said housing and extending through the open end thereof, said member having an eye on the opposite end thereof, and a pair of latches pivotally mounted in said housing for normally holding said headed member from passing entirely out of said housing, said housing having internal ribs thereon and said headed member having a squared shank portion to prevent relative turning of said members.

In witness whereof, I hereunto subscribe my name this 22nd day of April, A. D. 1924.

ARTHUR F. O'CONNOR.
